[57] **CLAIM**

The ornamental design for a tire, as shown and described.

DESCRIPTION

FIG. 1 is a perspective view of a tire showing our new design, it being understood that the tread pattern is repeated uniformly throughout the circumference of the tire as shown schematically by solid lines;

FIG. 2 is an enlarged fragmentary perspective view of the tread pattern thereof; and,

FIG. 3 is a side elevational view thereof, shown at a reduced scale, the opposite side elevational view being identical thereto.
